COMPRESSOR UNLOADER

Charles S. Baker, Corning, N. Y., assignor to
Ingersoll-Rand Company, Jersey City, N. J., a
corporation of New Jersey

Application October 20, 1932, Serial No. 638,750

7 Claims. (Cl. 230—25)

This invention concerns unloading systems for compressors and more particularly a system for proportional unloading by holding the intake valve of the compressor open for a greater or lesser period of the compression stroke of the piston. In order to accomplish this result it is proposed to connect the receiver to pressure actuated valve lifters of a common type adapted to hold the inlet valves in open position. A pressure fluid control valve in the line between the receiver and the valve lifters prevents operation of the latter until pressure in the receiver has been built up to a predetermined point.

A timing device inserted in the pressure line between the control valve and valve lifter intermittently opens the connection in the pressure line and then closes it simultaneously opening a relief port whereby pressure behind the valve lifter may be exhausted to atmosphere. Pressure actuated means responsive to receiver pressures are connected to the timing device or controller to advance or retard the period of operation of the valve lifter.

It is an object of the invention to provide means for the proportional unloading of a compressor by interference with the normal action of the valves during a greater or lesser portion of the piston cycle as the situation requires. This interference consists of holding the inlet valve open during part of the compression stroke so that, in effect, the compressor is short stroked and a smaller volume of fluid is supplied to the receiver. It is the purpose of the invention to make such interference with the normal valve action begin at a predetermined receiver pressure and to increase as the pressure increases. By increase of interference is meant the prolonging of the period of the compression stroke during which normal operation is suspended.

The construction and operation of the proportional unloading device above mentioned may be more readily understood by reference to the accompanying drawing in which,

Fig. 1 represents a somewhat diagrammatic side view of a reciprocal compressor in which the compressor cylinder is shown in section,

Fig. 2 is a sectional view of the timing device and its pressure actuated control, and

Fig. 3 is another sectional view of the timing device taken on the line 3—3 of Fig. 2 and looking in the direction of the arrows.

Referring to the drawing, a compressor cylinder designated generally by 5 is provided with a piston chamber 6 in which reciprocates a piston 7 having a piston rod 9 connected by a con-

necting rod 11 to a crank 13. Rotation of the crank 13 imparts a reciprocating motion to the piston 7. Connected to the piston chamber 6, by means of inlet valves 15, is an inlet manifold 17 provided with an air intake 19. Similarly the piston chamber 6 is connected by means of exhaust valves 21 to an exhaust manifold 23 having an outlet pipe 25 which conducts pressure fluid to a receiver or tank 27.

The apparatus thus far described is a simple compressor of the reciprocating type provided with the usual inlet and exhaust valves and adapted to discharge into a storage tank or receiver. In this standard equipment it is proposed to fit the inlet valves 15 with valve lifters 29. The valve lifters 29 are of a well known type, commonly referred to as free air unloaders. They consist of a fork 31 adapted to bear upon the valve and to hold it off its seat. The shank of the fork 31 is affixed to a plunger 33 which is 20 slidable in a bore 35 in a valve cap 37. Pressure fluid to actuate the plunger 33 is admitted to the bore 35 through the valve cap 37 by suitable connections 39.

Mounted on a bracket 41 on the compressor 25 casing 8 is a sylphon 43 the interior of which is suitably connected to the receiver 27 by a conduit 45. The sylphon is connected by a rod 47 to the short arm of the lever 49 which is pivoted to the end of an upturned extension 51 of the 30 bracket 41.

Inserted in a pipe 53 is a pressure operated valve 55 which is adapted to open when a predetermined pressure is attained in the receiver 27. In the present application the pipe 53 is fitted 35 with branch arms 54 which lead into a distributor or controller generally designated as 57 which is suitably mounted upon the casing 8. Pipes 56 lead from connections on the distributor to connections 39 on the free air unloaders. 40

Keyed to a shaft 59 of an engine (not shown) is a gear wheel 61 which is connected by a chain 63 to a similar gear wheel 65 upon the controller 57 so that the distributor may be driven in synchronism with the compressor.

A link 67 connects the lever arm 49 to a lug 69 on the distributor 57 to permit automatic adjustment of the latter. A spring 71 supported by the extension 51 and provided with an adjustment 73 bears against the arm 49 in opposition 50 to the pressure within the sylphon 43.

The distributor or timing device 57 consists essentially of an enclosed cylindrical valve or rotor 75 adapted to rotate in a casing or stator 77. The valve 75 is provided with extension shafts 55

79 to one of which is attached the gear wheel 65. The shafts 79 may be journalled in bearings 81 supported by arms of a support frame 83. The casing 77 is fitted with a cover plate 78 so that it completely encloses the valve 75.

5 The pipes 54 and 56 are connected to appropriate apertures in the casing 77. For the purpose of maintaining balance the pipes 54 in the present instance enter the casing 77 at points approximately 180° apart, but in order to avoid interference they are laterally spaced from each other. Similarly the pipes 56 are connected to the stator 77 in such a manner that each pipe 56 is in the same plane as its corresponding pipe 54. The 10 cylindrical valve or rotor 75 is provided with parallel peripheral slots 85 in order that communication between each pipe 54 and its mate 15 56 may be established at 180° intervals of crank-shaft rotation.

20 In the casing 77 and in alignment with each pair of pipes 54 and 56 are exhaust ports 58 which are adapted to open communication upon rotation of the valve 75 between the pipes 56 and the outside atmosphere thereby permitting pressure fluid from the back of the plungers 33 to escape through the pipes 56 and their appropriate valve slots 85 to atmosphere.

25 During the operation of the compressor the timing device or controller 57 is continually in operation, but no fluid may pass through it and it performs no useful function until the receiver pressure reaches a point where the valve 55 is opened and pressure fluid passes from the receiver 27 through the pipes 54. It may be noted here that the pipes 54 and 56 are all fitted with 30 flexible sections 60 at the stator connection to permit limited rotation of the casing 77 in response to movement of the link 67.

35 Rotation of the casing 77 is automatically provided by the sylphon through the linkage 47, 49 and 67 acting upon the lug 69 which extends from the casing 77. When the receiver pressure inside the sylphon is sufficient to overcome the 40 resistance of the spring 71 the sylphon expands and raises the short arm of the lever 49 and depresses the long arm, which acts through the link 67 upon the lug 69, thereby forcing the casing 77 to turn in a counter-clockwise direction which has the effect of retarding (with respect 45 to the compressor cycle) the exhaust from the pipe 56 through the outlets 58, whereby the valve 15 is maintained in open position during a portion of the compression stroke of the piston 7. The operation of the device may be briefly summarized as follows:

50 The crankshaft 59 and its attached toothed wheel 61 rotate in a counter-clockwise direction and this rotation is communicated through the chain 63 and the gear wheel 65 to the rotary valve 75.

55 Rotation of the crankshaft also causes reciprocation of the piston 7 in piston chamber 6. Each stroke of the piston compresses air on one side thereof and sucks air into the piston 60 chamber on the other side thereof. The inlet and exhaust valves open and close automatically in response to pressure changes in the piston chamber caused by movement of the piston.

65 Air pumped by the compressor is forced into 70 the receiver 27 where its pressure is increased. After the pressure reaches a predetermined point limited by the resistance of the valve 55 air from the receiver flows to the controller 57 as previously described. At a point in the compression cycle just after an intake valve has opened the

slot 85 of the rotor opens communication between a pipe 54 and a pipe 56. Air at receiver pressure then flows to the valve lifter 29 and operates it as hereinbefore set forth. The pressure behind the valve lifter holds the inlet valve open until the slot 85 has closed communication with pipe 54 and established communication with the exhaust port 58 which action is timed to be somewhat later than the normal time of automatic closing of the inlet valve. Air is then exhausted 10 from the valve lifter and the inlet valve closes permitting compression during the remainder of the piston stroke. This tardy closing of the valve reduces the pumping power of the compressor and results in a slower increase of pressure in the receiver. 15

Assuming that pressure continues to build up in the receiver the communicated pressure within the sylphon then causes this instrument to expand overcoming the resistance of the spring 71. 20 Expansion of the sylphon working through its connecting linkage causes a limited counter-clockwise movement of the casing 77. As the casing moves counterclockwise all of the pipe connections and exhaust ports are retarded with 25 respect to the crankshaft position and consequently with respect to the period of piston travel. The action of the valve lifters 29 are consequently retarded and the inlet valves 15 are held open for a longer period of the compression stroke. It will be seen that the interference with normal valve action may be made to vary in proportion to the pressure in the receiver.

Having thus described my invention I do not desire to be limited to the specific structure disclosed but claim:

1. In a compressor, a cylinder, a piston reciprocable therein, automatic inlet valves normally opened and closed in response to pressures created by reciprocation of the piston, a receiver 40 for pressure fluid discharged by the compressor, individual pressure responsive means for each inlet valve to delay automatic closing of the inlet valve until the piston has traveled through part of its compression stroke, and a rotary distributing device responsive to receiver pressure to control the distribution of pressure fluid to the said means and thus the duration of said delay.

2. In a compressor, a cylinder, a piston reciprocable therein, automatic inlet valves normally opened and closed in response to pressures created by reciprocation of the piston, individual pressure responsive means for each inlet valve to delay automatic closing of the inlet valve until the piston has traveled through part of its compression stroke, and means comprising a rotary timing device responsive to fluid pressure to regulate the admission of pressure fluid to the first said means and thus the period of delay.

3. In a compressor, a cylinder, a piston reciprocable therein, an inlet and an outlet valve, a receiver for pressure fluid, means controlled by fluid pressure for holding the inlet valve open during part of the compression stroke of the piston, a rotary timing device operating synchronously with the compressor piston for admitting pressure fluid to the valve holding means, and means responsive to pressure in the receiver to control the action of said timing device to advance or delay with respect to the cycle of the piston the time of admission of pressure fluid to the valve holding means.

4. In a compressor, a cylinder, a piston re-

5 ciprocable therein, an inlet and an outlet valve in the cylinder, a receiver for pressure fluid discharged from the compressor, individual pressure responsive means for each inlet valve for holding the inlet valve open during part of the compression stroke of the piston, and means comprising a rotary distributor responsive to receiver pressure to regulate the flow of pressure fluid to the pressure responsive means and thus 10 control the duration of opening of the inlet valve during the compression stroke.

10 5. In a compressor, a cylinder, a piston reciprocal therein, an inlet and an outlet valve for the cylinder, a receiver for pressure fluid discharged from the compressor, pressure fluid means to hold the inlet valve open during part of the compression stroke of the piston, a prime mover for the compressor, a rotary timing device operated by the prime mover to time the 15 action of the valve holding means and means responsive to pressure in the receiver to advance and retard the action of the timing device.

20 6. In combination with a compressor and the like, a cylinder, a piston, an inlet and an exhaust valve in the cylinder, a pressure actuated valve lifter attached to a plunger reciprocal in a bore, a conduit to admit pressure fluid into the bore, a distributor interposed in the conduit to control the flow of pressure fluid to and from 25 the valve lifter in a timed cycle of operations, said distributor having a stator element provided

with a connection to a source of pressure fluid, a connection to the valve lifter bore and a vent to the atmosphere, and a rotor in the stator rotating in fixed relationship to the compressor piston and having a peripheral slot which successively opens communication between the pressure source connection and the valve lifter connection and between the valve lifter connection and the atmospheric vent.

30 7. In combination with a compressor and the like, a cylinder, a piston, an inlet and an exhaust valve in the cylinder, a pressure actuated valve lifter attached to a plunger reciprocal in a bore, a conduit to admit pressure fluid into the bore, a distributor interposed in the conduit to control the flow of pressure fluid to and from the valve lifter in a timed cycle of operations, said distributor having a stator element provided with a connection to a source of pressure fluid, a connection to the valve lifter bore and a vent to the atmosphere, a rotor in the stator rotating in fixed relationship to the compressor piston and having a peripheral slot which successively opens communication between the pressure source connection and the valve lifter connection and between the valve lifter connection and the atmospheric vent, and means to adjust the stator with respect to the rotor to change the time relationship between the valve lifter and the piston.
